COMBINATION JEWELRY DISPLAY TRAY
AND TISSUE PAPER CONTAINER

Carl Weissman, Bronx, N. Y.

Application October 22, 1949, Serial No. 5,644

Term of patent 14 years

(Cl. D80—5)

To all whom it may concern:

Be it known that I, Carl Weissman, a citizen of the United States, residing at the Bronx, in the county of Bronx and State of New York, have invented a new, original, and ornamental Design for a Combination Jewelry Display Tray and Tissue Paper Container, of which the following is a specification, reference being had to the accompanying drawing, forming part thereof.

Fig. 1 is a perspective view of a combination jewelry display tray and tissue paper container, showing my new design;

Fig. 2 is a longitudinal cross sectional view through the tray with its hinged, recessed cover in elevated position and with the display supporting pad, normally resting in the recess of the cover, shown in slightly removed position; and

Fig. 3 is an enlarged fragmental cross section taken on line 3—3 of Fig. 1.

My design for combination jewelry display tray and tissue paper container shown resides in the inner ornamental framing of the display pad in which this framing carries out the ornamental grooved motif of the outer frame of the article, all as illustrated.

I claim:

The ornamental design for a combination jewelry display tray and tissue paper container, as shown and described.

CARL WEISSMAN.
